No. 740,113.

PATENTED SEPT. 29, 1903.

W. L. FERGUSON.
LANTERN HOLDER.
APPLICATION FILED MAR. 6, 1903.

NO MODEL.

THE NORRIS PETERS CO., PHOTO-LITHO., WASHINGTON, D. C.

UNITED STATES PATENT OFFICE.

WALTER L. FERGUSON, OF MARQUETTE, KANSAS.

LANTERN-HOLDER.

SPECIFICATION forming part of Letters Patent No. 740,113, dated September 29, 1903.

Application filed March 6, 1903. Serial No. 146,574. (No model.)

To all whom it may concern:

Be it known that I, WALTER L. FERGUSON, a citizen of the United States, residing at Marquette, in the county of McPherson and 5 State of Kansas, have invented certain new and useful Improvements in Lantern-Holders, of which the following is a specification.

This invention relates to lantern-holders, and pertains particularly to a wagon lantern-holder of special design adapted to be applied to the end of a wagon tongue or pole.

The object of the invention is to provide a device to flexibly hold a lantern of ordinary type to a wagon tongue or pole and admit of 15 the lantern being placed and removed without adjusting or removing the holder from the tongue.

A further object of the invention is to provide a lantern-holder having peculiar spring-20 arms terminating in tips and a pole ring or socket carried by lateral projections of the arms.

In the accompanying drawings, forming part of this application, Figure 1 is a perspective view showing the application of the 25 holder. Fig. 2 is a side elevation of the holder, showing one of the arms unhooked. Fig. 3 is a rear view of the holder.

The same numeral references denote the 30 same parts throughout the views of the drawings.

The lantern shown is of ordinary construction, except the back 1 thereof has an upper opening or aperture 2 therethrough, and like 35 openings 3 are made through the lower portion thereof.

The lantern-holder has a stem 4, provided with a sleeve or ring 5, having a set-screw 6, whereby the holder is secured to the front 40 end of a wagon tongue or pole 7, or said stem may be made in the form of a socket or sleeve and the ring dispensed with. Lateral projections 8 diverge from the front end of the stem 5, and at the intersection of the said 45 projections and the stem is formed an upwardly-turned hook 9 to engage the upper

opening 2 of the lantern-back. Spring-arms 10 are bowed from the projections 8 and terminate in downwardly-turned lips 11, which engage the lower openings 3 in the lantern- 50 back.

It is obvious that after the holder is once fixed to a tongue or pole the lantern may be hung to the holder by hooking it over the hook 9 and compressing the spring-bows so 55 as to insert the lips in the opening 3. To remove the lantern, the bows are compressed to lift the lips out of their openings, and the hook 9 is withdrawn.

It will be seen that the holder while capable 60 of adjustment on the pole is not disturbed in placing and removing the lantern.

Having thus described my invention, what I claim as new, and desire to secure by Letters Patent, is—

1. A lantern-holder comprising a stem having lateral projections, an upturned hook, spring-arms terminating in lips, and means for securing the holder, said lips and hook adapted to engage coöperating parts of the 70 lantern.

2. The combination, with a lantern having upper and lower apertures, of a holder having a hook to engage the upper aperture, spring-arms terminating in lips to engage the lower 75 apertures, and means for securing the holder.

3. The combination with a lantern having an upper opening, and lower openings, of a holder having a stem, lateral projections from the stem, an upturned hook at the intersection of the stem and projections to engage the upper opening, spring-arms extending from the projections and terminating in downwardly-turned lips to engage the lower openings, and means to secure the holder to a 85 wagon tongue or pole.

In witness whereof I hereunto set my hand in the presence of two witnesses.

WALTER L. FERGUSON.

Witnesses:

O. E. HAWKINSON,
G. W. ECKER.
